Patented Sept. 1, 1914.

UNITED STATES PATENT OFFICE.

HENRY C. HOLTHOFF, OF RIVERSIDE, ILLINOIS, ASSIGNOR, BY MESNE ASSIGNMENTS,
TO ALLIS-CHALMERS MANUFACTURING COMPANY, A CORPORATION OF DELAWARE.

TIMBER-TREATING APPARATUS.

1,109,334.

Specification of Letters Patent.

Patented Sept. 1, 1914.

Application filed October 14, 1911. Serial No. 654,759.

To all whom it may concern:

Be it known that I, HENRY C. HOLTHOFF, a citizen of the United States, residing at Riverside, in the county of Cook and State 5 of Illinois, have invented a certain new and useful Improvement in Timber-Treating Apparatus, of which the following is a specification.

This invention relates to improvements in 10 the construction of timber treating apparatus, and more particularly to improvements in the construction of piling or tie cars and to means for securing the bails thereto.

The object of the invention is to provide 15 a means for securing the bails of tie or piling cars to the body portions thereof, which is simple in construction, efficient in operation, and which will permit ready removal of the bails from the bail-carrying arms.

20 A clear conception of several embodiments of the invention can be had by referring to the drawing accompanying and forming part of this specification, in which like reference characters designate the same or similar parts in the various views.

Figure 1 is an end view of a tie car showing the bail and bail arms connected by securing means, built in accordance with the present invention. Fig. 2 is an enlarged central vertical section through a fragment of the bail, bail-carrying arm and connecting link between the members. Fig. 3 is an enlarged side view of a fragment of a bail and bail-carrying arm showing the connecting means 35 between the members. Fig. 4 is an enlarged central vertical section through a fragment of the bail and bail-carrying arm showing a modified form of connection between these members.

40 The tie or piling car consists essentially of a sheet metal body portion carried by wheels 4 and provided with upwardly directed bail-carrying arms 2, see Fig. 1. The bail-carrying arms 2 are also formed of sheet metal 45 and are provided with reinforcing ribs 5, formed of sheet metal having a U-shaped cross section. Protecting guards or plates 3 extend inwardly from the bail-carrying arms 2 and serve as protecting hoods for the 50 wheels 4. The bail 1 which is semicircular in shape, has its ends downwardly directed and extending for a short distance into the ends of the bail-carrying arms 2.

The securing means between an end of the 55 bail 1 and a bail-carrying arms 2, consists

essentially of a stop-carrying member 9, a hook 7, and a link 6. The stop-carrying member 9, which is preferably formed of cast metal, is provided at its lower end with inwardly projecting lugs 10, and is adapted to 60 fit snugly into the end of the bail-carrying arm 2. The member 9, see Figs. 1 and 2, spans the interior of the bail-carrying arm 2 and is fastened thereto by means of rivets 12 or other suitable fastening means. The 65 end of the bail-carrying member 2 and the stop-carrying member 9 coact so as to form a recess into which the end of the bail 1 can be freely inserted.

The hook 7 is provided with an inwardly 70 projecting lower portion 11 which extends under the lower end of the member 9. The upper end of the hook 7 is provided with a stop 8 which normally coacts with the upper end of the member 9, thereby preventing 75 dropping of the hook 7 beyond a predetermined position. The upper hooked portion of the hook 7 is adapted to take over the link 6 which is mounted upon the bail 1 and is adapted to swing outwardly therefrom. 80

In the modified form of securing means between the bail 1 and bail-carrying arm 2, see Fig. 4, the stop-carrying member 9 has been entirely omitted. The transverse bolt 15 spans the interior of the bail-carrying 85 member 2 and forms a stop for the end of the bail 1. The hook 17 is provided with stops 18, one on either side, which project over the upper side edges of the bail arm 2, thereby preventing dropping of the hook 17 90 beyond the desired position. The lower end of the hook 17 has a projection 19 which extends under the transverse bolt 15, while the upper hooked portion of the hook 17 takes over the link 6 which is secured to the 95 bail 1 in a manner similar to that above disclosed.

In order to remove the bail 1 from the bail-carrying members 2, it is necessary only to raise the hooks 7 until the portions 11 100 contact with the members 9, and to swing the links 6 on either side of the car outwardly so as to be free from coaction with the adjacent hooks. The bail 1 can then be easily lifted upwardly out of the sockets 105 formed in the members 9, by means of the links 6 which during removal of the bail serve as removing handles. In placing the bail 1 in position, the ends of the bail 1 are inserted into the sockets formed in the mem- 110

bers 9, being permitted to rest upon the stops 10. The hooks 7 are then raised until the portions 11 contact with the lower ends of the members 9 when the links 6 are permitted to swing into contact with the sides of the hooks 7. The hooks 7 are then permitted to drop back into the position shown in Fig. 2. The insertion and removal of the device disclosed in Fig. 4 is identical with that just explained, the differences between the devices of Figs. 1 and 4 being structural and not affecting the operation.

If the piling car after having been loaded with timber, is placed into a treating cylinder and submerged in the treating liquid, as is customary in the process of treating timber, the timber has a tendency to float, thus tending to raise the bails 1 away from the car. It will be noted that with the constructions disclosed, such tendency to raise the bails 1 will cause the hooks 7, 17, to be drawn upwardly until the projections 11, 19, contact with the lower surfaces of the member 2 and bolt 15, after which a further rise of the bails 1 is prevented. The projections 11, 19, after removal of the car from the liquid, recede from their stops, the hooks again taking the normal positions as shown in the drawing.

It should be understood that it is not desired to be limited to the exact details of construction shown and described, for obvious modifications will occur to a person skilled in the art.

It is claimed and desired to secure by Letters Patent,

1. In a timber treating car, a bail arm, a bail, a link having a swinging connection with said bail, and hook means movably supported by but locked relatively to said bail arm, said hook means being detachably connected to said link.

2. In a timber treating car, a hollow bail arm, a member extending into the hollow

portion of said arm, a bail extending into said arm and coacting with said member to be stopped thereby, and a hook adapted to extend under said member and to connect with said bail to unite said bail and bail arm.

3. In a timber treating car, a bail arm member, a bail member, a link secured to one of said members, the other of said members having definite stops thereon, and a hook carried by and freely movable between said stops and detachably connected with said link.

4. In a timber treating car, a hollow bail arm, a stop within the hollow portion of said arm, a bail contacting with said stop, and a hook extending under said stop and connecting with said bail to unite said bail and arm.

5. In a timber treating car, a bail arm having definite stops thereon, a bail, a link secured to said bail, and a hook carried by said bail arm and freely movable between said stops, said hook being detachably connected with said link.

6. In a timber treating car, a bail arm, a bail, a link having swinging connection with said bail, and a hook slidably mounted in said bail arm and contacting with said link, said hook being detachable from said link.

7. In a timber treating car, a bail member, a bail arm member, one of said members having definite stops thereon and one of said members having a stop for the other of said members, and a hook carried by and movable freely between said definite stops and engageable with the other of said members.

In testimony whereof, the signature of the inventor is affixed hereto in the presence of two witnesses.

HENRY C. HOLTHOFF.

Witnesses:

THOMAS A. DALEY,

J. GERAGHTY.
